TREE STAND

Clifford S. Ford, Arlington, Va.

Application April 13, 1954, Serial No. 29,978

Term of patent 14 years

(Cl. D35—3)

To all whom it may concern:

Be it known that I, Clifford S. Ford, have invented a new, original, and ornamental Design for a Tree Stand, of which the following is a specification, reference being had to the accompanying drawing, forming a part hereof.

I claim:

The ornamental design for a tree stand, as shown.
